DESIGN FOR A HOUSING OF A TWO-CYCLE GAS ENGINE

Melvin F. Schmidt, Saginaw, Mich.

Application March 22, 1945, Serial No. 118,641

Term of patent 7 years

(Cl. D71—1)

To all whom it may concern:

Be it known that I, Melvin F. Schmidt, a citizen of the United States, residing at Saginaw, in the county of Saginaw and State of Michigan, have invented a new, original, and ornamental Design for a Housing of a Two-Cycle Gas Engine, of which the following is a specification, reference being had to the accompanying drawing, forming part thereof.

In the drawing,

Fig. 1 is a front perspective view of a two-cycle gas engine showing my new design.

Fig. 2 is a rear elevational view.

Fig. 3 is a rear elevational view thereof.

I claim:

The ornamental design for a housing of a two-cycle gas engine, as shown.

MELVIN F. SCHMIDT.
